UNITED STATES PATENT OFFICE

2,471,024

CHAIR WITH TILTING BACK AND AUTOMATICALLY SHIFTABLE SEAT

Roy A. Cramer, Kansas City, Mo.

Application October 4, 1946, Serial No. 701,320

19 Claims. (Cl. 155—77)

1

This invention relates to chairs and more particularly to improvements in posture chairs of the general type having automatically tilttable backs.

One of the objects of the present invention is to provide a novel posture chair construction which combines an automatically tilttable back and shifttable seat in such a manner that an exceedingly comfortable action is achieved when the chair is in use.

A further object of the invention is to provide a chair of the above type wherein, as the back is tilted rearwardly, the seat automatically moves forwardly, thus securing an easy and natural pivotal action of the upper and lower portions of the user's body substantially about the hip joints.

Another object resides in the provision of a chair having a novel construction which insures that during tilting of the back, the seat will automatically shift forwardly and the chair back will automatically follow the movements of the user's back, in order to eliminate all tendency toward objectionable back-rub.

A further object includes the novel feature of maintaining the correct balance of the chair and its occupant with respect to the chair base during all angles of tilt of the chair back.

Still another object resides in providing a chair of the foregoing character which includes in addition to the automatically tilttable back and shifttable seat, a construction which enables the seat to be initially adjusted forwardly or rearwardly with respect to the chair support or pedestal and independently of the back, this arrangement providing a ready adjustment to accommodate the chair to different size persons.

A still further object comprehends a novel chair construction including relatively few parts which are relatively simple in construction and which may be economically manufactured and assembled.

Other objects and features of the invention will appear more fully hereinafter from a consideration of the following detailed description when taken in connection with the accompanying drawings wherein a preferred embodiment of the invention is illustrated. It is to be expressly understood however that the drawings are employed for purposes of illustration only, and are not designed as a definition of the limits of the invention, reference being had for this purpose to the appended claims.

In the drawings, wherein similar reference

2

characters refer to similar parts throughout the several views;

Fig. 1 is a side view, partly in section, of a chair constructed in accordance with the present invention, and illustrating the normal position of the back and seat;

Fig. 2 is a view similar to Fig. 1, showing the position of the parts when the back is tilted and the seat shifted forwardly;

Fig. 3 is a plan view, partly in section of the bottom of the seat and adjusting members associated therewith;

Fig. 4 is a partial sectional view taken substantially along line 4—4 of Fig. 3;

Fig. 5 is a plan view of the bottom of the chair plate;

Fig. 6 is a transverse sectional view taken substantially along line 6—6 of Fig. 5, and

Fig. 7 is a transverse sectional view taken substantially along line 7—7 of Fig. 5.

Referring more particularly to Figs. 1 and 2, a chair constructed in accordance with the principles of the present invention is illustrated therein as comprising a base or supporting pedestal 10 having a seat spider 12 secured to the upper end thereof, the said spider being formed to support a cushioned seat 14 and a back 16, in a novel manner which will appear more fully hereinafter. It will be understood that the pedestal 10 is adapted to be supported by any suitable type of base, the arrangement being such that the pedestal and hence the height of the seat, may be adjusted vertically, in a conventional manner.

One of the dominant features of the present invention, as illustrated in Figs. 1 and 2 resides in the novel construction and cooperation of the seat spider 12, the seat 14 and the chair back 16, the arrangement being such that as the back 16 automatically tilts from the position shown in Fig. 1 to the solid line position shown in Fig. 2, the seat 14 automatically shifts forwardly as illustrated in this latter figure.

In addition to such forward shifting of the seat, it will be seen from Fig. 2, that the rear portion of the seat shifts downwardly a slight distance, this action being clear from an inspection of the normal position of the seat and back, shown in dotted lines, and the automatically adjusted position, shown in full lines, which the parts assume as the back is tilted rearwardly.

In use, the automatic movement of the parts, above referred to, is achieved as the occupant 55 presses the back 16 rearwardly with a predeter-

mined effort, the operation resulting is an exceedingly comfortable action accompanied by the entire elimination of back rub. If desired, the chair may be equipped with a pair of arm rests, one of which is shown at 19, and preferably the arm rests are carried by portions 21 and 21a, Fig. 3, of the tiltable back 16, this arrangement further increasing the comfortable action when the chair is in use. It is also preferred that the back 16 be provided with a cushioned back rest 18 which may automatically tilt about a horizontal axis in any suitable manner, such as for example, as shown in my application Serial Number 690,498, filed August 14, 1946, for Chair back. The back rest may also be adjustable vertically as by means of a hand wheel 20, in order that it may readily be accommodated to the most comfortable position with relation to the back of the occupant.

In order to secure the above highly desirable results, and referring to Figs. 3 and 4, the back 16 is formed with an upstanding post 17 for receiving the back rest 18, and a pair of arms 22 and 24 which are positioned beneath the seat 14 and extend forwardly on either side of the pedestal 10. As shown, the forward extremities of the arms 22 and 24, are pivotally connected, as by means of a shaft 26 to a pair of forwardly extending arms 28 and 30, formed integrally with the spider 12. With such an arrangement, it will be readily perceived that the back 16 may be tilted in the manner illustrated in Fig. 2, the arms 22 and 24 pivoting upon the shaft 26 and with respect to the stationary arms 28 and 30 of the spider 12.

Novel means are provided by the invention for slidably mounting the seat 14 upon the seat support including the spider 12, and one of the important features resides in associating the seat with the tilting back 16 in such manner as to secure the automatic forward shifting of the seat as the back 16 tilts to the position illustrated in full lines in Fig. 2. As shown, such means includes a channel shaped adjusting member 32 having a pair of spaced apart plates 34 and 36 connected by a base portion 38, the said plates being pivotally connected to rearwardly extending arms 40 and 42 of the spider 12, as by means of a shaft 44. In a manner to be more particularly referred to hereinafter, the seat 14 is supported upon a plate 46 having a pair of depending brackets 48 and 50 secured thereto, the latter being pivotally connected to the plates 34 and 36 as by means of a rod 52 positioned above and in substantial vertical alignment with the shaft 44. The forward portions of each of the plates 34 and 36 are respectively provided with cam slots 54, one of which is shown in Fig. 4, and within these slots, cam rollers 56 and 58 are positioned, the latter being carried by arms 22 and 24 of the back 16 in any suitable manner, such as by means of stub shafts 60. From this arrangement, it will be readily seen that as the back 16 is tilted, and the arms 22 and 24 pivot downwardly about the shaft 26, the cooperation between the cam rollers 56 and 58 and the slot 54 will cause the adjusting member 32 to pivot in a clockwise direction about the shaft 44. Such pivotal action of member 32 causes the brackets 48 and 50, plate 46 and seat 14 to shift downwardly and forwardly as heretofore pointed out in connection with Fig. 2. Such shifting of the seat, relative to the spider 12, is readily enabled by providing the plate 46 with a pair of depending guide channels 62, 64 which are positioned to receive and guide rollers

66 and 68 respectively, carried by the ends of shaft 26.

In order to maintain the parts in the position shown in Figs. 1, 3 and 4, and to yieldingly resist the back-tilting and seat-shifting movements, the present invention provides a pair of expanding springs 70 and 72 which are interposed between the base 38 of the adjusting member 32 and a cross-head 74 operatively connected with the seat spider 12. More particularly, each of the springs 70 and 72 is provided with an internal support including a rod and sleeve construction 76, while an adjustment of the tension of springs 70 and 72 is secured by an adjusting wheel 78 having a part 80 threadedly engaging a brace 82 formed integrally with the arms 28 and 30 of the spider. As the hand-wheel 78 is adjusted to move the cross-head 74 toward the brace 82, the tension of the springs 70 and 72 is increased and hence the force required to tilt the back 16 and shift the seat 14 is likewise increased. Thus, desirable variations in spring tension may be readily secured by a simple adjustment, readily accessible at the forward part of the chair.

Means are provided to limit the return movement of the seat, when the back 16 returns to the normal upright position, and preferably such means is so arranged as to be shock absorbing in character. As shown, such means includes stop flanges 84 and 86, respectively formed on the guide channels 62 and 64, a block of rubber 88 being preferably secured to the rear faces of the flanges to engage the forward ends of the arms 22 and 24 as the seat is moved rearwardly and returned to normal position.

In addition to the foregoing novel features, the present invention also provides a construction whereby the horizontal position of the seat with respect to its supporting base and the back, may be varied in order to widen or narrow the seat depth to suit the particular user. In the form of the invention illustrated, see Figs. 5, 6 and 7, such construction includes an adjustable hand screw 90, which when adjusted, is capable of moving the seat 14 forwardly or rearwardly with respect to the plate 46.

More particularly, the seat 14 includes a seat plate 92 having a pair of spaced apart guide rails 94 and 96 secured thereto and engaging the top adjacent opposite edges of the plate 46. Spacer strips 98 and 100 are secured to the rails 94 and 96 respectively, and as shown in Figs. 5 and 7, additional guide rails 102 and 104 are respectively secured to the strips 98 and 100 over a substantial part of the rear portions of the strips to form enclosed guides for slidably securing the seat plate 92 to the plate 46. A bracket 106 is secured to the plate 46 in any suitable manner and is provided with a depending part 108 threadedly engaging the hand screw 90. In order to shift the seat plate 92, as the hand screw 90 is threaded in or out with respect to the part 108, the hand screw carries suitable abutments or stops which engage a lug 110 secured to the seat plate 92 as by screws 112. In the form shown, such stops include washers 114 and 116 together with cotter pins 118 and 120, although it will be understood that any suitable type of stop may be used for the purpose of sliding the seat plate 92 with respect to the plate 46 as the hand screw 90 is adjusted.

From the foregoing, it will be understood that to adapt the chair to any particular person, it is only necessary that the person sit in the chair whereupon the depth of the seat and the vertical

position of the back rest may be readily adjusted to the most comfortable positions. For example the first named adjustment may be secured by rotating the hand screw 90 in order to shift the seat plate 92 forwardly or rearwardly with respect to the plate 46 to correspondingly increase or decrease the depth of the seat. During such operation, the hand screw 90 is threaded into or out of the bracket 106 and the seat plate 92 is shifted through the cooperation between the stop washers 114 and 116 and the lug 110. When the seat shifts, the enclosed guides formed by the parts 94, 96 and 102 on the one hand and parts 96, 100 and 104 on the other slide along the opposite edges of the plate 46.

Following these initial adjustments, it is only necessary to adjust the tension of springs 70 and 72 by operation of the hand wheel 78 in order to obtain the desired resistance to tilting of the back. It is here noted that due to the shape of the cam slots 54 with which the cam rollers 56 and 58 co-operate, the back 16 is normally maintained in an upright or posture position with a predetermined force which must be overcome by a predetermined pressure against the back rest before tilting of the back occurs. This will be clear when it is seen that the contour of the slot 54 at 122 is extended toward the left beneath the cam roller, see Fig. 4, and hence an appreciable force must be exerted before the cam rollers 56 and 58 may be moved from the upper ends of the cam slots 54, during forward pivoting of the adjusting member 32. If desired the contour at 122 may be so shaped as to provide an increased resistance before tilting action of the back may be secured, it being only necessary to curve the cam slots further to the left beneath the cam rollers at 122 as seen in Fig. 4.

In operation, the parts occupy the normal, upright or posture position illustrated in Figs. 1, 3 and 4. Should the occupant exert the predetermined pressure sufficient to overcome the tension of springs 70 and 72, the back 16 may be tilted to the full line position shown in Fig. 2 whereupon the seat 14 will be shifted forwardly as heretofore pointed out, such action being secured through the association of the adjusting member 32 with the cam rollers 56 and 58 carried by arms 22 and 24 of the back and through the connection with the seat 14 by means of the brackets 48 and 50 and the shaft 52. Due to the concurrent movements of the back and seat, it will be understood that an exceedingly comfortable action is secured. In particular, it will be seen that as the back is tilted and the upper portion of the occupant's body moves rearwardly of the pedestal 18, the forward shifting of the seat, carries the lower portion of the occupant's body forwardly. Thus the center of weight will be maintained over the pedestal of the chair and any tendency toward unbalance, by reason of tilting of the back, is eliminated.

There has thus been provided by the present invention, a novel posture chair construction embodying a variety of advantageous features, all of which cooperate to increase the comfort of the occupant. For example, the tiltable back is so arranged with respect to the seat, as to automatically shift the latter forwardly as the back tilts rearwardly, thereby resulting in an easy, natural action on the part of the occupant. Such operation moreover increases the stability of the chair, since the center of weight is maintained over the pedestal at all times. A further desirable feature insures the elimination of all back

rub during the tilting action, this being secured by the combined movements of the back and seat and the pivotal movement of the back rest.

While the invention has been shown and described herein with considerable particularity, it will be understood by those skilled in the art, that various changes and modifications thereof may be resorted to without departing from the spirit of the invention. Reference will therefore be had to the appended claims for a definition of the limits of the invention.

What is claimed is:

1. A chair comprising a support, a seat slidably mounted on said support, a back pivotally connected with the support beneath the seat so as to be capable of tilting movement, and means interconnecting the back and seat for moving the latter forwardly with respect to the support as the back is tilted rearwardly.
2. A chair comprising a supporting pedestal, a seat spider carried by the upper end of the pedestal and provided with a pair of forwardly extending arms, a seat slidably mounted on the spider, a back, means for pivotally connecting the back to said arms so as to be capable of tilting movement, and means interconnecting the back and seat for moving the latter forwardly with respect to the spider as the back is tilted rearwardly.
3. A chair comprising a support, a seat slidably mounted on said support, a back pivotally connected with the support beneath the seat so as to be capable of tilting movement, an operative connection between the back and seat for moving the latter forwardly with respect to the support as the back is tilted rearwardly, and resilient means beneath the seat for normally maintaining the back in normal upright position and yieldingly resisting the tilting movement thereof.
4. A chair comprising a supporting pedestal, a seat spider carried by the upper end of the pedestal and provided with a pair of forwardly extending arms, a seat slidably mounted on the spider, a back, means for pivotally connecting the back to said arms at the forward ends thereof so as to be capable of tilting movement, means operatively connecting said spider, back and seat for moving the latter forwardly with respect to the spider as the back is tilted rearwardly, and resilient means beneath the seat for normally maintaining the back in normal upright position and yieldingly resisting the tilting movement thereof.
5. A chair comprising a support, a seat slidably mounted on said support, a back pivotally connected with the support beneath the seat so as to be capable of tilting movement, and means including an adjusting member pivotally connected with the support and the seat and operatively connected with the back for moving the seat forwardly with respect to the support as the back is tilted rearwardly.
6. A chair comprising a supporting pedestal, a seat spider carried by the upper end of the pedestal and provided with a pair of forwardly extending arms, and a pair of rearwardly extending arms, a seat slidably mounted on the spider, a back, means for pivotally connecting the back to the forwardly extending arms so as to be capable of tilting movement, and means including an adjusting member pivotally connected with said rearwardly extending arms and the seat and operatively connected with the back for moving the seat forwardly with respect to the support as the back is tilted rearwardly.
7. A chair comprising a supporting pedestal, a seat spider carried by the upper end of the pedes-

tal and provided with a pair of forwardly extending arms, and a pair of rearwardly extending arms, a seat slidably mounted on the spider, a back having a substantially upright part at the rear of the seat and a pair of arms positioned beneath the seat, means for pivotally connecting the back to the forwardly extending arms so that the back is capable of tilting movement, an adjusting member pivotally connected with said rearwardly extending arms, means for pivotally connecting said adjusting member and seat, and means carried by said back arms and operatively connected with said adjusting member for moving the latter about the first named pivotal connection to move the seat forwardly as the back is tilted rearwardly.

8. A chair as defined in claim 7 including in addition, resilient means interposed between the adjusting member and said forwardly extending arms for normally maintaining the back in normal upright position and yieldingly resisting the tilting movement thereof.

9. A chair comprising a supporting pedestal, a seat spider carried by the upper end of the pedestal and provided with a pair of forwardly extending arms, a back having an upright part and a pair of arms arranged substantially parallel to the first named arms, means including a shaft pivotally connecting the forward ends of all of said arms so that the back is capable of tilting movement, a seat positioned above said spider, means including a pair of rollers carried by opposite ends of said shaft for supporting the seat for slidable movement with respect to the spider, and means pivotally connected with said spider and operatively connected with the seat and the arms of the back for moving the seat forwardly with respect to the spider as the back is tilted rearwardly.

10. A chair comprising a supporting pedestal, a seat spider carried by the upper end of the pedestal and provided with a pair of forwardly extending arms, a back having an upright part and a pair of arms arranged substantially parallel to the first named arms, means including a shaft pivotally connecting the forward ends of all of said arms so that the back is capable of tilting movement, a seat positioned above said spider, means including a pair of rollers carried by opposite ends of said shaft for supporting the seat for slidable movement with respect to the spider, means for sliding the seat forwardly with respect to the spider upon rearward tilting movement of the back, and resilient means beneath the seat for normally maintaining the back in normal upright position and yieldingly resisting the tilting movement thereof.

11. A chair comprising a supporting pedestal, a seat spider carried by the upper end of the pedestal and provided with a pair of forwardly extending arms, a back having an upright part and a pair of arms arranged substantially parallel to the first named arms, means including a shaft pivotally connecting the forward ends of all of said arms so that the back is capable of tilting movement, a seat positioned above said spider, means including a pair of rollers carried by opposite ends of said shaft for supporting the seat for slidable movement with respect to the spider, an adjusting member pivotally connected with said spider, means for pivotally connecting said adjusting member and seat, and means carried by the arms of the back and operatively connected with said adjusting member for moving the latter about the first named pivotal connection to move the seat forwardly as the back is tilted rearwardly.

12. A chair comprising a supporting pedestal, a seat spider carried by the upper end of the pedestal and provided with a pair of forwardly extending arms, a seat slidably mounted on the spider, a back, means for pivotally connecting the back to said arms so as to be capable of tilting movement, and means for moving the seat forwardly with respect to the spider as the back is tilted rearwardly, said means including a plate pivotally connected with said spider, means pivotally connecting said plate to the seat, and means interconnecting the back and plate to move the plate about the first pivotal connection.

13. A chair comprising a supporting pedestal, a seat spider carried by the upper end of the pedestal and provided with a pair of forwardly extending arms, a seat slidably mounted on the spider, a back, means for pivotally connecting the back to said arms so as to be capable of tilting movement, and means for moving the seat forwardly with respect to the spider as the back is tilted rearwardly, said means including an adjusting member having a pair of spaced-apart parallel plates each formed with a cam slot, means for pivotally connecting said plates with said spider and seat at spaced apart points, and a pair of cam rollers carried by said back and positioned within said cam slots.

14. A chair comprising a support, a substantially horizontal plate slidably mounted on the support, a seat slidably mounted on the plate, a back pivotally connected with the support beneath the plate so as to be capable of tilting movement, means interconnecting the back, support and plate for moving the plate and seat mounted thereon forwardly with respect to the support as the back is tilted rearwardly, and means for initially slidably adjusting the position of the seat with respect to the plate.

15. A chair comprising a support, a substantially horizontal plate slidably mounted on the support, a seat slidably mounted on the plate, a back pivotally connected with the support beneath the plate so as to be capable of tilting movement, means interconnecting the back, support and plate for moving the plate and seat mounted thereon forwardly with respect to the support as the back is tilted rearwardly, and means comprising cooperating threaded members carried by said seat and plate respectively for initially adjusting the position of the seat with respect to the plate.

16. A chair comprising a supporting pedestal, a seat spider carried by the upper end of the pedestal and provided with a pair of forwardly extending arms, a seat slidably mounted on the spider, a back, means for pivotally connecting the back to said arms so as to be capable of tilting movement, and means for moving the seat forwardly with respect to the spider as the back is tilted rearwardly, said means including an adjusting member having a substantially vertically arranged curved cam slot, and a cam member carried by the back and cooperating with said slot.

17. A chair comprising a support having a seat mounted thereon for sliding movement with respect thereto, a back for the chair, means for pivotally connecting the back with the support so that the back may tilt rearwardly with respect to the seat, resilient means normally acting to maintain the back in an upright position and yieldingly resisting tilting movement thereof, a part pivotally connected with the support and the seat, and means including a connection between said

back and said part for moving the latter about the pivotal connection with the support to slide the seat forwardly with respect to the support as the back tilts rearwardly.

18. A chair as set forth in claim 17 wherein said connection includes a cam slot formed in said part and a member carried by the back and received in the slot.

19. A chair as set forth in claim 18 wherein the resilient means is positioned between the support 10 and said part.
